CLAIM

The ornamental design for a shelf bin retaining wall, as shown.

DESCRIPTION

FIG. 1 is a perspective view of a shelf bin retaining wall showing my new design;

FIG. 2 is a top plan view thereof;

FIG. 3 is a front elevational view thereof;

FIG. 4 is a rear elevational view thereof;

FIG. 5 is a bottom plan view thereof;

FIG. 6 is a left side elevational view, the right side being a mirror image thereof; and

FIG. 7 is a perspective view thereof, the showing in broken lines being for environmental purposes only.

FIG-1

FIG-2
